UNITED STATES PATENT OFFICE.

OSCAR S. KULMAN, OF SAVANNAH, GEORGIA.

DESIGN FOR A BROOM-COVER.

SPECIFICATION forming part of Design No. 31,530, dated September 19, 1899.

Application filed August 18, 1899. Serial No. 727,708. Term of patent 7 years.

To all whom it may concern.

Be it known that I, OSCAR S. KULMAN, a citizen of the United States, residing at Savannah, in the county of Chatham and State of Georgia, have invented and produced a new and original Design for Broom-Covers, of which the following is a specification, reference being had to the accompanying drawings, forming part thereof, and in which—

10 Figure 1 is a side view of a broom-cover, showing my new design. Fig. 2 is a longitudinal section taken on line 2 2 of Fig. 1, and Fig. 3 is a transverse section taken on line 3 3 of Fig. 1.

15 As shown in the drawings, the leading or material feature of my design consists of a flattened tube A of tapered form with straight

walls, having a longitudinally arranged lapped seam a¹, an opening a¹ at its smaller end, and an extension-flap a², attached to one 20 of its side walls at its larger end.

Having thus described my invention, what I claim as new, and desire to secure by Letters Patent, is—

The design for a broom-cover as herein 25 shown and described.

In testimony whereof I have signed my name to this specification in the presence of two subscribing witnesses.

OSCAR S. KULMAN.

Witnesses:

ALBERT NUSSBAUM,
AAHRON KOHLER.
